FURNACE STOKER

Joseph S. Bennett, Merion, Pa., assignor to American Engineering Company, Philadelphia, Pa., a corporation of Pennsylvania

Original application October 23, 1934, Serial No. 749,539. Divided and this application September 22, 1937, Serial No. 165,057

10 Claims. (Cl. 122—4)

This application is a division of my co-pending application Ser. No. 749,539, filed October 23, 1934, and the invention here involved relates to stoker furnaces, and more particularly to stokers having fluid cooling means associated therewith for preventing clogging of the tuyère openings by slag and clinker formations. The ash content of certain types of coals, it has been found, not only fuses at a comparatively low temperature, but forms an impervious mass when cooled which clogs the air openings of the grates as well as impairs the operation of the stoker as a whole. In many cases it is necessary to extinguish the fire at frequent intervals so that the slag and clinker masses adhering to the grates may be removed.

One object of the present invention is to provide means for preventing such damage to the grates and to insure efficient burning of all fuels.

Another object is to provide in an underfeed stoker a plurality of fluid conducting tubes disposed in cooling relation with the tuyère rows and extension grates to prevent injury thereto by the furnace heat and clinker formations.

A further object is to provide a stoker of the continuous ash discharge type wherein the entire exposed surface thereof is effectively cooled by fluid conducting means.

Other and further objects will become apparent as the description of the invention progresses.

Of the drawings:

Fig. 1 is a longitudinal sectional view taken through a furnace, showing one type of fluid cooled stoker of the continuous ash discharge type.

Fig. 2 is a plan view taken substantially along line 2—2 of Fig. 1, and

Fig. 3 is a longitudinal sectional view of a stoker of a modified construction.

Referring to the drawings, the numeral 1 designates a furnace having provided therein an underfeed stoker 2, comprising alternately disposed retorts 3 and tuyère rows 4. Fuel is fed into the retorts 3 from hoppers 5 by any suitable feeding mechanism, partially indicated at 6, and operated by any suitable power mechanism (not shown). The fuel entering the retorts 3 is underfed over the length thereof by pushers 8, and the extension grates 9 provided at the rear end of the stoker overfeed the fuel through a discharge opening 41 provided in the rear or bridge wall 13 of the furnace. As shown in Figs. 1 and 2, a series of fluid conducting tubes 25 are mounted on the tuyère blocks of each of the tuyère rows 4. The upper ends of tubes 25 extend verti-

cally a short distance adjacent the front wall of the furnace and terminate in a header 26 suitably supported in said wall. These vertical extensions of the tubes cool the portions of the wall adjacent the inlet passages to the retorts and minimize the formation and growth of clinkers thereon. The lower ends of tubes 25 continue downwardly at a slightly steeper angle and are disposed in cooling relation with a series of fixed extension grates 31; the movable extension grates 9 being in alignment only with the retorts and thus are not in contact with the tubes. The tubes 25 terminate at the lower ends thereof in a header 35 supported in any suitable manner beneath extension grates 9 and 37. Connected to and extending rearwardly of header 35 are a series of tubes 38, the substantially horizontal portions 38' of which form a shelf which receives the consumed fuel fed from the extension grates 9 and 37, while the substantially vertical portions 38'' thereof are connected at their lower ends to a header 39 mounted in any suitable manner upon a support 40. The bridge wall 13, as shown in Fig. 1, terminates above the tubes 38 and has provided therein a series of fluid conducting tubes 14. The lower ends 14' of these tubes form the exposed surface of the upper wall of passage 41, and terminate in a header 16. The tubes 14 are bent, as shown at 14'', and extend upwardly and form the exposed surface of bridge wall 13. The upper ends of these tubes may be connected to a header, or directly to a boiler (not shown). Headers 16 and 39 are connected to the boiler by downcomer connections 16' and 39' respectively, while header 26 is connected to said boiler by riser connection 26A.

Fig. 3 shows a construction somewhat on the order of that shown in Figs. 1 and 2, except that the tubes 25' provided on tuyère rows 4' extend rearwardly of the stoker, as shown at 38A, forming a portion of a shelf which receives the residue fed from the stoker. In this construction the extension grates 9 and 37, shown in Figs. 1 and 2, are dispensed with, and the lower ends of tubes 25' terminate in a header 39A supported at 40'. A header 35' is supported in any suitable manner beneath the lower end of the stoker, which receives the upper ends of an alternately disposed series of tubes 42 disposed in substantial alignment with the retorts 3'. These tubes 42 extend in parallel relation with the extended portions 38A of tubes 25' and also terminate at their lower ends in header 39A. In this construction a series of refractory elements 43 are secured to tubes 25' and 42, as shown in Fig. 3. These ele-

ments are mounted in spaced relation, forming openings therebetween through which draft air may pass, as indicated by the arrows in Fig. 3. The plenum chamber beneath the stoker is divided into compartments 44 and 45 by a wall 46. Air enters chamber 44 through an inlet passage 41, a portion of which may pass into chamber 45 through the opening 48 provided in wall 46. The amount of air flowing into compartment 45 may be regulated by a damper 49 operated by a rod 50. Under certain conditions it may be desirable to provide pressure means to cause a more rapid circulation of fluid in the tubes 25' and 42 of the stoker. To this end a booster pump 101 is provided which, as shown in Fig. 3, is connected to the boiler (not shown) by a downtake connection 102 and feeds fluid under pressure to header 39^A through pipe 103. Headers 35' and 26' are connected to the boiler by riser connections 35^A and 26^B, respectively. The substantially horizontal section 38^A is spaced from the lower end of bridge wall 13', thus providing a passage 41' through which the refuse from the stoker is fed. The exposed surface of bridge wall 13' also has provided therein a series of fluid conducting tubes 14^A which extend forwardly and upwardly from a header 16^A. The upper ends of tubes 14^A may be connected to a header or directly to one of the steam drums of a boiler (not shown).

The constructions herein shown and described not only lower the maintenance cost of stokers, but permit furnaces to operate for long periods of time without interruption. These constructions are especially desirable when the fuels burned are of the type wherein the ash content thereof fuses at low temperatures. This molten ash has a tendency to clog the tuyère openings, and thus prevents the proper amount of air to enter the fuel bed. This also causes considerable damage to the grates with the result that the maintenance cost is not only high, but a considerable loss is experienced in taking the boilers off the line to make the necessary repairs. The constructions herein shown have largely eliminated these undesirable conditions and have also increased the efficiency of the units as well.

While the invention is shown applied to stokers of the underfeed type, it is believed to be apparent that it is equally adaptable for use in other types of stokers as well. The invention therefore is not to be limited to the embodiments herein shown since it may be embodied in other forms, all coming within the scope of claims which follow.

What is claimed is:

1. In a furnace, the combination of a rear wall having a transverse recess provided at the lower end thereof, a front wall, a stoker inclining downwardly and rearwardly from said front wall, a longitudinal extension provided at the rearwardly disposed end of said stoker, said extension extending into the recess provided in said rear wall and forming with the lower end of the latter a passage, and means for fluid cooling said stoker and rear wall.

2. In a furnace, the combination of a rear wall having a transverse recess provided at the lower end thereof, a front wall, a stoker inclining downwardly and rearwardly from said front wall, said stoker consisting of alternately disposed retorts and tuyère rows, an extension provided at the lower end of said stoker and extending into the recess provided in said rear wall, said extension being disposed in spaced relation with the lower

end of said rear wall and forming therewith a passage, said extension comprising a series of fluid conducting tubes, and means comprising a series of fluid conducting tubes mounted on the exposed surfaces of said rear wall. 5

3. In a furnace, the combination of a rear wall having a transverse recess provided at the lower end thereof, a front wall, a stoker inclining downwardly and rearwardly from said front wall, said stoker consisting of alternately disposed retorts 10 and tuyère rows, an extension provided at the lower end of said stoker and extending into the recess provided in said rear wall, said extension being disposed in spaced relation with the lower end of said rear wall and forming therewith a 15 passage, said extension comprising a series of fluid conducting tubes, means comprising one or more tubes mounted in cooling relation with said tuyère rows, headers connecting the opposite ends of said tubes, and means comprising a series of 20 fluid conducting tubes mounted on the exposed surface of said rear wall.

4. In an underfeed stoker, comprising alternately disposed retorts and tuyère rows, of alternately disposed fixed and moving extension 25 grates mounted at the rear end of said retorts and tuyère rows, fluid conducting tubes mounted over said tuyère rows and fixed extension grates, upper and lower headers for receiving the opposite ends of said tubes, a second series of fluid 30 conducting tubes connected to and extending rearwardly of said lower header forming a shelf for supporting the fuel fed by said extension grates, and a series of fluid conducting tubes provided above and in spaced relation with said shelf 35 forming therewith a passage through which the fuel discharging from said stoker may pass.

5. In an underfeed stoker, comprising alternately disposed retorts and tuyère rows, of means for feeding fuel to said retorts and tuyère rows, 40 one or more fluid conducting tubes mounted over each tuyère row, the lower ends of said tubes extending rearwardly forming a support for the fuel fed from said stoker, said tubes terminating at their lower ends in a header, a second header for the upper ends of said tubes, a third header disposed near the lower end of said retorts and tuyère rows, a series of tubes extending rearwardly of said header and in parallel relation with the extensions of said first mentioned tubes, 50 and terminating in said header first named, and a series of fluid cooled tubes mounted above and in spaced relation with said support and forming therewith a discharge passage for the fuel discharging from the stoker. 55

6. In an underfeed stoker, comprising alternately disposed retorts and tuyère rows, of means for feeding fuel to said retorts and rows of tuyères, one or more fluid connecting tubes mounted in cooling relation with the tuyères of each of 60 said rows, the lower ends of said tubes extending rearwardly and forming a support for the fuel fed from said stoker, said tubes terminating at their lower ends in a header, a second header for the upper ends of said tubes, a third header disposed near the lower end of said retorts and tuyère rows, a series of tubes extending rearwardly of said header and in parallel relation with the extensions of said first mentioned tubes and terminating in said header first named, and 70 means for supplying fluid to at least one of said headers.

7. In an underfeed stoker, comprising alternately disposed retorts and rows of tuyère blocks, of means for feeding fuel to said re- 75

- torts and rows of tuyère blocks, one or more fluid conducting tubes mounted in cooling relation with the tuyère blocks of each of said rows, the lower ends of said tubes extending rearwardly, forming a support for the fuel fed from said stoker, said tubes terminating at their lower ends in a header, a second header for the upper ends of said tubes, a third header disposed near the lower ends of said retorts and tuyère rows, 5 10 15 20 25 30
- 10 a series of tubes extending rearwardly of said header and in parallel relation with the extensions of said first mentioned tubes and terminating in said header first named, a boiler, means for connecting said headers to said boiler, and a booster pump for feeding fluid under pressure from said boiler to one of said headers.
8. In an underfeed stoker, comprising alternately disposed retorts and rows of tuyère blocks, of alternately disposed, fixed and movable extension grates mounted at the rear end of said retorts and rows of tuyère blocks, one or more fluid conducting tubes mounted in cooling relation with the tuyère blocks of each of said rows and said fixed extension grates, upper and lower headers connecting the opposite ends of said tubes, a second series of fluid conducting tubes connected to and extending rearwardly of said lower header forming a shelf for supporting the fuel fed by said extension grates, a header connecting the other end of last last mentioned
- tubes, and means for supplying fluid to said last mentioned header.
9. In an underfeed stoker, comprising alternately disposed retorts and rows of tuyère blocks, of alternately disposed fixed and movable extension grates mounted at the rear end of said retorts and rows of tuyère blocks, one or more fluid conducting tubes mounted in cooling relation with the tuyère blocks of each of said rows and said fixed extension grates, upper and lower 10 15 20 25 30
- headers for receiving the opposite ends of said tubes, a series of fluid conducting tubes connected to and extending rearwardly of said lower header forming a shelf for supporting the fuel fed by said extension grates, and a series of fluid conducting tubes provided above and in spaced relation with said shelf forming therewith a passage through which the fuel discharging from said stoker may pass.
10. In a furnace, the combination of a rear wall having a transverse recess provided at the lower end thereof, a front wall, a stoker inclining downwardly and rearwardly from said front wall, a longitudinal extension provided at the rearwardly disposed end of said stoker, said extension being disposed beneath the lower end of said rear wall and forming therewith a passage, and means for fluid cooling said stoker.

JOSEPH S. BENNETT. 30
